(57) **CLAIM**

The ornamental design for a cover accessory for cellular telephones and similar articles, as shown.

DESCRIPTION

FIG. 1 is a first perspective view of an ornamental cover accessory for cellular telephones and similar articles.

FIG. 2 is a top plan view thereof.

FIG. 3 is a first side view thereof.

FIG. 4 is a first end view thereof.

FIG. 5 is a second end view, opposite the first end view thereof.

FIG. 6 is a bottom plan view thereof; and,

FIG. 7 is a second side view, opposite the first side view thereof.

Any broken line portions of the drawings are not part of the claimed design.
